UNITED STATES PATENT OFFICE.

ANDREW G. PETERSON, OF WAHPETON, NORTH DAKOTA.

CISTERN.

No. 876,392.

Specification of Letters Patent.

Patented Jan. 14, 1908.

Application filed June 29, 1906, Serial No. 324,069.

To all whom it may concern:

Be it known that I, ANDREW G. PETERSON, a citizen of the United States, residing at Wahpeton, in the county of Richland and State of North Dakota, have invented a new and useful Cistern, of which the following is a specification.

The present invention relates to cisterns or reservoirs for the storage of water and other liquids, and it relates more particularly to cisterns constructed of concrete or other self hardening plastic materials.

The invention has for its objects to improve and simplify devices of this character, so that they are easy to construct, substantial and durable, inexpensive to manufacture, and readily accessible for cleaning.

With these objects in view, and others, as will appear as the invention is better understood, the same comprises the various features of construction and arrangement of parts described hereinafter and set forth with particularity in the claims appended hereto.

25 In the accompanying drawing, which illustrates one embodiment of the invention, Figure 1 is a semi-vertical section and elevation of the cistern more particularly adapted for underground use. Fig. 2 is a detail view of a 30 portion of the tank for adapting the same for above ground use. Fig. 3 is a detail view of the self closing valve for the end of the inlet pipe.

Corresponding parts in the several figures 35 are indicated throughout by similar characters of reference.

Referring to the drawing, 1 represents the main or bottom portion of the cistern, which in transverse horizontal section may be circular or polygonal, as desired, the cylindrical shape being preferable. Arranged on the top of the body 1 of the cistern is a cover 2 shaped in the form of a cap with a contracted throat 3 that is closed by a cap or plate 4. The body and top of the cistern are each formed 45 of plastic material made of one part of Portland cement and one and a half parts of sand. These proportions are satisfactory for certain results, but may be changed, and also other 50 materials may be employed, if desired. Suitable forms are provided for molding the parts of the cistern, as will be readily understood.

55 Embedded in the walls of the body 1 and cover 2 are iron members 5 for the purpose of reinforcing the walls so as to withstand the pressures subjected to them. The members

5 in the body 1 each comprises a strip of iron of suitable cross section that extends diametrically of and embedded in the bottom of the body and extends upwardly from the 60 ends of the bottom portion 6 to form side portions 7 that are embedded in the cylindrical wall of the body 1. The extremities of the reinforcing irons are preferably continued outwardly through and beyond the 65 exterior surface of the body to form lugs 8. In the present illustration, two reinforcing irons are shown, they being arranged diametrically of the cistern and in planes disposed at right angles to each other. It is obvious 70 that any number of these reinforcing irons may be employed, and further, any two opposite side portions 7, instead of being connected by a common base or bottom portion 6, may be separate. The cover 2 has also 75 embedded in its walls a plurality of reinforcing irons 5 that are arranged in the same planes with the irons in the body 1, so that the lugs 10 formed by their lower ends projecting outwardly from the cover, will align 80 with the lugs 8. The lugs 8 and 10 are provided with registering perforations to receive the bolts 11, which latter hold the cover securely on the cistern body. The joint between the cover and body is formed by an 85 annular groove in one of them, which is V-shaped in a radial direction and the other member is correspondingly shaped to fit the groove. Such a joint forms a perfect seal when the cover is securely bolted to the body. 90

For further reinforcing the cistern, the body 1 and cover 2 are provided with a number of circumferential hoops or bands 12 arranged in any desired manner. The neck 3 of the cover is formed with an annular 95 shoulder 13 against which fits a correspondingly shaped shoulder 14 on the cover plate 4. The cover plate may be held in place by its own weight, or by any suitable device, as desired. Extending into the cistern through 100 the cover are pipes 15 and 16, the same snugly fitting in openings in the cover plate for receiving them. The pipe 15 serves to convey the water or other liquid to be stored into the cistern, and extends only a short 105 distance below the cover plate. It is provided with a self closing valve 16' fulcrumed at 17 on a lug 18 and maintained in normally closed position by the adjustable counterbalance weight 19. The valve is so weighted 110 that it will automatically open under the weight of liquid in or flowing through the

pipe 15, but will close as soon as the pipe becomes empty, thereby sealing up the latter and preventing air from entering the cistern. The pipe 16 extends almost to the bottom 5 of the cistern, so as to draw the water or other liquid from the latter by means of a pump. The pump pipe is employed when the cistern is sunken in the ground, or in the basement of a building, or in any place where 10 the liquid will have to be lifted from the cistern.

In order to adapt the cistern for use at a point more or less elevated above the floor or ground, a connection may be made with the 15 cistern adjacent the base thereof at a point indicated at 20, Fig. 2. This connection may supply one or more faucets located more or less remote from the cistern in a suitable pipe system, as will be readily understood, or a faucet, 21, as shown, may be applied directly to the cistern at the point 20.

I have described the principle of the invention, together with the apparatus which I now consider to be the best embodiment 25 thereof, but I desire to have it understood that the apparatus shown is merely illustrative, and that various changes in the materials, arrangement of parts, and proportions may be resorted to, as are within the scope 30 of the invention. I also desire to have it understood that the term cistern is to be construed to mean any receptacle or reservoir, for water or other liquids, of all sizes, from tubs to railroad tanks.

35 What is claimed is—

1. A cistern comprising a hollow body made of plastic material in one homogeneous piece, and a plurality of reinforcing metal strips embedded in said body, each metal 40 strip extending diametrically across the bottom of said body, then up the sides in a vertical direction to a point near the top, the ends thereof being bent outwardly to project in a

radial direction through and beyond the exterior face of the cistern wall to form attach- 45 ing lugs.

2. A cistern comprising a hollow body and cover each made of plastic material in one homogeneous piece, a plurality of reinforcing metal strips embedded longitudinally 50 in the side wall of said body, the upper end of each reinforcing strip bent outwardly to project through and beyond the exterior face of the body wall, a plurality of metal reinforcing strips embedded in said cover 55 and in alinement throughout their length with those in the body and bent outwardly at their lower ends to project through and beyond the wall of the cover, and means for connecting each reinforcing strip in said body to an alined strip in the cover.

3. A cistern comprising a body and separable cover each made of plastic material, a plurality of reinforcing metal strips embedded longitudinally in the side wall of said body, 65 the upper end of each reinforcing strip bent outwardly to project through and beyond the exterior face of the body wall, a plurality of metal reinforcing strips embedded in said cover and in alinement throughout their 70 length with those in the body and bent outwardly at their lower ends to project through and beyond the wall of the cover, means for connecting each reinforcing strip in said body to an alined strip in the cover, and reinforcing bands extending horizontally around the exterior of said body and cover and partly 75 embedded in the substance thereof.

In testimony that I claim the foregoing as my own, I have hereto affixed my signature 80 in the presence of two witnesses.

ANDREW G. PETERSON.
